Primary Examiner — W. A. Teddy Falloway

(74) Attorney, Agent, or Firm — Womble Bond Dickinson (US) LLP

(57) **CLAIM**

The ornamental design for a blade dispenser, as shown and described.

DESCRIPTION

FIG. 1 is a front perspective view of a blade dispenser of the present invention showing my new design;

FIG. 2 is a front side elevation view thereof;

FIG. 3 is back side elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines illustrate portions of the blade dispenser that form no part of the claimed design.
